UNITED STATES PATENT OFFICE.

FREDERICK S. WHITNEY, OF NEW YORK, N. Y.

ATTACHMENT FOR CABLE-RECORDERS.

1,350,193.

Specification of Letters Patent. Patented Aug. 17, 1920.

Application filed March 25, 1918. Serial No. 224,686.

To all whom it may concern:

Be it known that I, FREDERICK S. WHITNEY, a subject of the King of England, residing at New York, in the county of New York and State of New York, have invented new and useful Improvements in Attachments for Cable-Recorders, of which the following is a specification.

This invention relates to attachments for submarine cable recorders, and the object is to provide certain novel means under the control of the usual rotatable coil whereby the solenoids of the tape punching devices are more effectively controlled than by apparatus now in use.

A further object is to provide for the control of a plurality of relays and circuits, certain of which include a vibrator, by means of contact making elements comprising a disk member or pan rotatable on a vertical axis mounted in jewels and carrying pins or tongues coöperating with stationary contact elements for completing a circuit and actuating means for punching a continuous row of apertures in the middle of a tape; certain of the pins or tongues completing a circuit energizing means for indicating at the required time the dots of the Continental or International code, and certain of said pins or prongs completing a circuit energizing means for indicating dashes, the various operations specified being independent of each other.

With the foregoing and other objects in view, the invention consists in the novel construction, combination and arrangement of elements hereinafter described and claimed.

In the accompanying drawings:—

Figure 1 is a top plan view showing the rotating coil connected with the rotatable disk or pan and showing the associated contact making elements.

Fig. 2 is a view of the structure shown at the right of Fig. 1, in section and side elevation.

Fig. 3 is an elevation of the recorder.

Fig. 4 is a front elevation of the recorder.

Fig. 5 is a diagrammatic view including the structure of Fig. 1 and the relays, the recorder coils, and the circuits for the elements specified.

The tape punching devices *per se* are not shown or described in this case, but it may be stated that the levers by which the punches are respectively controlled are

themselves actuated by levers 61, 64, 65 (Figs. 3, 4 and 5).

The structure shown at the left of Fig. 1 and the structure shown in Figs. 3 and 4 is 60 more or less conventional and of the general type now in use, the pole extensions of the magnet being designated 10 and 12, and the rotating coil between these poles being designated 16. This coil has connection by 65 means of fibers of silk or the like 15 with a rotatably mounted pan or disk of aluminum designated 17 and mounted on a staff 18 which in turn is mounted in jewels to permit of the free movement of the staff and 70 the pan mounted thereon, and adding greatly to the sensitiveness of the instrument.

A frame 20 supports the staff and serves 75 to mount the jewels, this frame being mounted above a plate or platform 21 supported by uprights 24. The frame is, however, mounted directly on a pedestal 23.

A plurality of threaded binding posts 80 are designated 25 and 26, these binding posts being provided with transverse bores carrying silver pointed contact screws 27, 28 projecting toward each other and engaged by brass contact members 29 and 30 carried by disk 17 at one side thereof.

A plurality of binding posts 32 and 33 are 85 also threaded transversely and accommodate adjusting screws 34, 35 each contacting with a pivotally mounted arm formed of brass, these arms being designated 38, 39 90 and being under the control of fine springs or hair springs 40. The pivotal mounting of these arms 38, 39 is at the point shown, and they approach each other at a point adjacent to the front side of the disk, as distinguished from the side or edge where contact members 29 and 30 are located. A pin or projecting member 42 of silver is located at the edge of the disk and between the projecting ends of arms 38 and 39.

It will be understood that the movement of the coil 16 causes a corresponding movement of the disk 17 in one direction or the other.

The vibrator of a given type may be of 105 substantially the form now in use except that I employ a device electro-magnetically controlled, but otherwise similar to that shown in United States Patent #1,043,449.

The projection or tongue 42 carried by 110 the pan is of silver and the swing of the recorder coil to either side causes the silver

tongue to open the arms 38 and 39, breaking contact on contact screws 34, 35, and opening contact on the vibrator.

A particular feature of the invention is the return of disk 17 to normal position under the influence of spring-held arms 38 and 39, either arm acting as the positive agent (depending upon the direction of movement), and the other as a cushioning device, thereby reducing jarring and false vibration of the elements, including coil 16, to a minimum. Elements 38 and 39 have therefore an important mechanical function, closely related to the electrical operation described below.

When the arms 38 and 39 are closed, they make contact on screws 34 and 35, closing contact on the vibrator specified, which in vibrating opens and closes by suitable means the circuit for the central solenoid designated 60, the core of this solenoid operating pivoted lever 61 controlling a suitable perforating device as in the well known type of such instrument. The other solenoid coils 25 are designated 62 and 63 and control respectively, through the cores thereof, pivoted levers 64 and 65, these each being mounted with lever 61 on a transverse shaft or the like designated 66 having its bearings in vertical posts or pillars 67 and 68. Each lever 61, 64 and 65 is designed to operate a perforating member for punching holes in a tape in the well known manner.

It should be stated that the vibrator operates only when the arms 38 and 39 are in contact with tongue 42 carried by the disk 17, the elements then being in the position shown in Figs. 1 and 5.

The brass contact tongues 29 and 30 carried by the rear portion of the disk 17 make contact on screws 27 and 28 when the coil 16 of the recorder is moved to either side continuously, completing indirectly the circuit for coils 62 and 63 of the perforating device.

The variation of the position of coil 16 by reason of the impulses received over the line wires causes the corresponding movement of disk or pan 17. Upon the completion of a local battery circuit and assuming that disk 17 is in its normal position, the coil 60 will be energized for punching a continuous row of apertures centrally of the tape. When the disk swings in either direction, coil 62 or 63 will be energized, as the case may be, and coil 60 will be deenergized so that only one of the levers 61, 64, 65 will operate at a given instant. Coils 62 and 63 punch apertures on opposite sides of the central row of apertures in the tape, and one of them is operated for the dashes and the other for the dots. The circuits for the coils last named are closed by relays controlled by local circuits through a local battery, and through the various contacts

controlled directly by disk 17. This local battery is designated 71 and the source of current for the 110-volt circuits for the solenoids is shown conventionally at 72.

The central row of holes is punched in the tape as a result of the operation of solenoid 60, the circuit being from local battery 71 through wire 73, wire 74, relay 60', wire 76, vibrator 77, wire 78, binding post 84, wire 79, binding post 83, screw 35, arm 39, pin 42, stem 18, wire 86, binding post 83, wire 87, to battery 71.

This will cause the vibration of armature 91 of relay 60' and the latter will intermittently complete a circuit through contact 91'.

Each time the circuit is completed through armature 91 and contact 91' coil 60 is energized by the 110-volt circuit, the source of power being shown conventionally at 72. The circuit from 72 is through wire 100, wire 101, coil 60, wire 102, contact 94' of armature 94, through that armature thence through wire 103, contact 93' armature 93 wire 104, to contact 91', armature 91, wire 105, wire 106, resistance 107, to source 72.

The purpose of solenoid 60 is to provide spaces or central holes between letters and words, providing for one space after each letter and three spaces after each word, as in the strip manually punched at the transmitting end. This arrangement is carried out in order to insure reliability in transmission. When disk 17 is in normal position and the circuit through pin 42 is closed, central holes are continuously punched in the strip. When the disk is moved to either side, dots or dashes are punched by the operation of solenoid 62 or 63, as the case may be, but when the pin 42 returns from a deflected position, or moves in a path crossing its normal position, central holes are punched in the strip as the direct result of the operation of the central solenoid. During the punching of apertures for dots and dashes, the central apertures may be punched mechanically in any well known manner.

When energizing solenoid 62 or 63 for punching the holes indicating dots or dashes, contact is made between pin 29 or pin 30 and the adjacent contact screw.

Assuming that the disk 17 swings in a given direction by reason of a corresponding movement of coil 16, contact is made between screw 28 and contact pin 30. A circuit is then completed through local battery 71, this circuit being through screw 28, binding post 26, wire 110, binding post 82, wire 111, the coil of relay 114, wire 115, the coil of relay 63' wire 116, wire 73, battery 71, wire 87, binding post 83 wire 86, stem 18, disk 17, contact 30, completing the circuit.

Contact is thereby broken at 93' and contact is made at 92' closing a circuit through wire 120, coil 62, of a solenoid operating the

dot punching device, wire 121, wire 100, source 72, wire 72', resistance 107, wire 106, armature 92, back to contact 92'. This circuit last named is energized while the circuit through coil 60 is momentarily broken at 93'.

The solenoid coil 63 of the dash punching device is operated in a similar manner, contact being made through contact element 95' when armature 95 is attracted by the magnet of relay 62'. Relay 62' is energized by a circuit through contact 29 and screw 27 when the disk 17 swings in a direction opposite to that previously mentioned.

The circuit through contact 29 is through disk 17, wire 86, binding post 83, wire 87, battery 71, wire 73, wire 74, the coil of relay 62' wire 125, the coil or relay 113, wire 126, binding post 81, wire 127, binding post 25, screw 27 to contact 29.

At this time the circuit through contact 94' is broken, deenergizing solenoid 60, and contact is made at 95' completing a circuit through solenoid 63, including source 72.

Starting from contact 95' the circuit is through wire 130, coil 63, wire 100, source 72, wire 72' resistance 107, wire 106, wire 131, and armature 95, to contact 95'.

Provision has therefore been made for energizing solenoid 60 for punching the central row of apertures in the tape, when the disk is in its normal position as shown at

Fig. 5. Provision has also been made for energizing solenoid 62 of the dot punching device, when the disk is swung to one side, and for energizing solenoid 63 when the disk is swung to the opposite side, neither of the solenoids being energized at the same moment.

It may be added that when the local battery 71 completes a circuit through wire 78 to stem 18, a portion of the current may pass through element 38, screw 34, and wire 87', binding post 85, wire 85', and wire 87, to 71.

What is claimed is:

1. In a device of the class described, a plurality of magnets, a coil mounted for rotation on a vertical axis between the poles of the magnet, a disk mounted for rotation on a vertical axis, the mounting means including a staff and mineral elements within which the staff is carried, contact members mounted on the disk, means connecting the disk with the coil and causing the disk to rotate in unison with the movement of the coil, a vibrating device and a recording device, contact members mounted in the path of movement of the contact devices first named upon the rotation of the disk, an additional contact element on the disk, and pivoted arms contacting therewith on oppo-

site sides thereof when the disk is stationary, an additional circuit and means for completing the latter through the vibrator and an element of the recording device and 65 through said arms, when the disk is stationary, the rotation of the disk moving either of the arms pivotally for breaking the circuit last named.

2. In a device of the class described, a 70 plurality of magnetic poles, a coil mounted for rotation on a vertical axis between the poles, a disk and means for moving the latter on a vertical axis in unison with the movement of the coil, a contact element on 75 the disk, a circuit including a battery and including the contact element and disk, the circuit being normally broken, a relay in said circuit, a second circuit including a solenoid and a source of current, and controlled by the relay, an additional contact carried by the disk, a second relay, means for completing a circuit through the second relay, the battery, and the contact last named, when the disk is stationary, said 80 means last named including a plurality of conducting arms resiliently engaging the contact last named on opposite sides thereof, a second solenoid, a circuit therefor controlled by the relay last named, and means 85 for supplying current to the second circuit independent of the source of current first named.

3. In a device of the class described, a 90 plurality of magnetic poles, a coil mounted 95 for rotation on a vertical axis between the poles, a disk mounted for rotation on a vertical axis, means for rotating the disk upon the movement of the coil upon its axis, a contact element carried by the disk, a solenoid for operating a punching device, means for completing a circuit through the contact, for energizing the solenoid when the disk is stationary, said means last named including a plurality of conducting arms 100 resiliently engaging the contact on opposite sides thereof, a plurality of additional contacts arranged in pairs, either pair being brought into operative relation upon the rotation of the disk in the direction in which 105 the movable contact of that pair moves to closed position, additional solenoids for operating other punching devices, and means for completing a circuit through either of said additional solenoids independently of 110 the other and of the solenoid first named, upon the movement of the disk in either direction, said means last named having connection with the additional contacts.

In testimony whereof I affix my signature. 120

FREDERICK S. WHITNEY.
